BUCKLE

Samuel E. Kelman, Providence, R. I.

Application July 14, 1950, Serial No. 11,316

Term of patent 7 years

(Cl. D17—1)

To all whom it may concern:

Be it known that I, Samuel E. Kelman, a citizen of the United States, residing at Providence, in the county of Providence and State of Rhode Island, have invented a new, original, and ornamental Design for a Buckle, of which the following is a specification, reference being had to the accompanying drawing, forming part hereof.

Fig. 1 is a front view of a buckle, showing my new design; and

Fig. 2 is an edge view of the same.

I claim:

The ornamental design for a buckle, as shown.

SAMUEL E. KELMAN.
